UNITED STATES PATENT OFFICE.

LEMUEL W. SERRELL, OF PLAINFIELD, NEW JERSEY.

CLOTHES-WASHER.

1,132,982.

Specification of Letters Patent. Patented Mar. 23, 1915.

Application filed February 12, 1914. Serial No. 818,188.

To all whom it may concern:

Be it known that I, LEMUEL W. SERRELL, a citizen of the United States, and a resident of Plainfield, in the county of Union and State of New Jersey, have invented certain new and useful Improvements in Clothes-Washers, of which the following is a specification.

This invention relates to that type of clothes-washing devices wherein a cup-shaped or conical member is moved up and down in the tub, thus alternately rarefying and compressing the air in the cup so as to force the water through the meshes of the fabric.

My object is to provide a simple and practical mechanical device operating on this principle, which is attachable to an ordinary tub and insures uniform and thorough washing of all the clothes. To this end the pneumatic cup is given a movement down, across and up within the tub, so as to distribute the clothes and bring them all under the action of the cup. In the mechanical embodiment of the invention the said cup is mounted on a plunger and carried by a pair of pivoted arms, which latter are so mounted and actuated by suitable mechanism as to swing from side to side past the vertical, thus moving the cup in a curved path from side to side and down and up. This movement causes the action of the cup to take place in different parts of the tub and also moves the clothes about so as to insure all the articles being acted upon.

In the accompanying drawings illustrating the preferred embodiment of the invention: Figure 1 is a plan view of the device as applied to an ordinary stationary wash-tub, the latter being shown broken away; Fig. 2 is a vertical section through the tub, showing the device in side elevation, with the exception of a portion that is broken away and sectioned; and Fig. 3 is a sectional elevation taken on the line 3—3 of Fig. 1.

The tub 4 is of the ordinary form usually built in pairs. For the attachment of the illustrated embodiment of my device, I secure a plate 5 to the board 6 at the back of the tub, this plate being preferably angled to fit the corner at the back of the tub and having openings 7 in its downwardly offset portion 8. A suitable form of support for the washing mechanism comprises a two-part bar or tube 9, 10, adapted to span the top of the tub and carrying at its outer ends

suitable means, such as shown at 11, 12, for attachment thereto. As illustrated, the member 11 comprises a plate having a split clamping collar portion 13, for the reception of the rear end of the tube 9, and downwardly-projecting pins 14 for removable insertion in the openings 7, the heads of these pins being extended forwardly as indicated in Fig. 2, so that when the bar is drawn forward the heads lock it in place at the rear. The member 12 has a similar clamping collar portion 15 to receive the forward end of the tube 10, and is further provided with a foot flange 16, to rest upon the top of the forward edge 70 of the tub, and a downwardly-projecting arm 17, through which is threaded a screw 18 to bear against the inclined front wall of the tub. The support also includes a frame 19, consisting of two parts or halves 20 and 21, which are secured at their lower portions to the inner ends of the tube sections 9 and 10 in a manner similar to that of securing the members 11, 12.

In the illustrated embodiment of the invention, the frame parts comprise spaced base members 22 having inturned meeting portions 23 at their ends suitably united by bolts 24. From the base members rise spaced standards 25 having inturned meeting parts 26 at their upper ends united in the same manner as the ends of the base portions.

While the foregoing support is regarded as desirable and is specifically claimed hereinafter, it will be understood that other forms of support may be adopted without departing from the main features of my invention.

A pair of swinging arms 27, 28 are disposed within the frame 19, being pivotally mounted at 32, 32', on the inner side of the frame pieces 20, so as to be capable of swinging from positions at one side of their vertical line of centers, approximately as indicated in Fig. 3, downward and upward to the reverse position at the opposite side. In this movement they carry with them a pneumatic cup 29, of suitable form, the latter being rigidly secured to the lower end of a plunger 30, which is pivoted to the outer ends of the arms, as shown at 31. Thus, by swinging the arms back and forth the cup is caused to travel in a curved path in a vertical plane, substantially as indicated by the broken lines in Fig. 3.

Either power or manual means may be provided for oscillating the mechanism.

For power drive the support need not span the top of the tub, but may be of other suitable character. In the illustrated construction, a rock-shaft 32 passes through the 5 tube section 10, being suitably journaled in bearings at its opposite ends and at its inner end carrying the lower arm 28, while its outer end is provided with a handle 33.

In order to insure the arms moving in 10 unison past the vertical line of centers, they are connected by gearing, which may comprise gears 34 and 35 fixed to the pivots or shafts of the arms and an intermediate idler gear 36 journaled on one of the uprights 15 25. Manifestly, a sprocket and chain, or other suitable form of mechanism, could be substituted with equal effect.

In operation, the tub is partially filled with water to about the level indicated, the 20 clothes are placed therein, and the attachment is applied in position. The operator then grasps the handle and moves it back and forth through an arc approximating 180°, thus moving the vacuum cup down 25 into the water, across and upwardly out and then backward in the same path, the movement being repeated as often as necessary. I have ascertained that this action is especially effective in washing clothes, since it 30 moves different portions of them from side to side, thus distributing and mixing them, so that by the time the washing is completed all have been acted upon uniformly.

It will be understood that I do not wish 35 to limit myself to the specific details of construction illustrated, and that various changes may be made without departing from the invention.

What I claim as new is:

40 1. A clothes-washer, comprising a stationary support having suitable means of attachment to a tub, a pneumatic cup, parallel arms pivoted on said stationary support and carrying said cup always in 45 vertical position, and means for moving said parallel arms back and forth past the vertical so as to move said cup back and forth in an arcuate path downward, across and upward, thereby dragging the clothes 50 alternately from side to side of the tub.

2. In a clothes-washer, the combination of a support, parallel arms mounted thereon to swing about horizontal axes, a pneumatic cup member carried by said arms, 55 and means for oscillating said arms back and forth past the vertical so as to cause the cup member to oscillate in an arcuate path downward, across and upward, so as to drag the clothes alternately from side to side at 60 each stroke.

3. In a clothes-washer, the combination of a pair of parallel swinging arms, a plunger carried thereby and bearing a pneumatic

cup, and means for oscillating said arms back and forth past the vertical so as to 65 cause the cup to oscillate in an arcuate path downward, across and upward whereby said arms are compelled to move at all times in unison.

4. In a clothes-washer, the combination 70 of a two-part bar adapted to span the top of a tub and having means of attachment thereto at its outer ends, a two-part frame, the members of which are secured to the inner ends of the parts of said bar, said frame 75 comprising spaced base members having meeting portions at their ends and uprights rising from said base members and having meeting portions at their tops, parallel arms disposed within said frame and pivotally 80 mounted on one of the parts thereof, gearing connecting said arms to swing in unison, a vacuum cup member carried by said arms, and suitable mechanism for operating said arms to swing said cup member 85 downward and upward from one side to the other of the vertical center line.

5. In a clothes-washer attachment for 90 tubs, the combination of a sectional bar adapted to span the tub and having means of attachment thereto at its ends, a frame intermediate of the sections of the bar, parallel arms mounted on said frame, a plunger and cup carried by said arms, and mechanism for swinging said arms back 95 and forth so as to carry said cup downward, across and up from side to side alternately.

6. In a clothes-washer attachment for 100 tubs, the combination of a sectional bar adapted to span the tub and having means of attachment thereto at its ends, a frame intermediate of the sections of said bar, parallel arms mounted on said frame to swing from side to side, a plunger and cup carried by said arms, a rock-shaft passing 105 through one of the sections, a handle on the outer end of said shaft, and gearing at the inner end thereof for operating said arms in unison.

7. In a clothes-washer attachment for 110 tubs, the combination of a tubular support having means of attachment to a tub, parallel arms mounted on said frame to swing from side to side, a plunger and cup carried by said arms so as to be moved downward, 115 across, upward and back repeatedly, and a rock-shaft for operating said arms within said tubular support.

In witness whereof I have signed my name in the presence of two subscribing 120 witnesses.

LEMUEL W. SERRELL.
